(57) **CLAIM**

The ornamental design for a handle for a chassis mounted server computer, as shown and described.

DESCRIPTION

FIG. 1 is a top, front and right side perspective view of a handle for a chassis mounted server computer in accordance with our design;

FIG. 2 is a top plan view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a bottom plan view thereof;

FIG. 8 is a top, front, right side perspective view thereof, on a reduced scale, the handle is shown in partially open position; and,

FIG. 9 a top, front, right side perspective view thereof, on a reduced scale, the handle is shown in a closed position.

The broken line illustrations of a server blade in FIG. 8 and FIG. 9 are used to indicate environmental structure and form no part of the claimed design.
